ABSTRACT: Disclosed is an apparatus in which a movable breaking or splitting tool moves between adjustably spaced supports on which may be positioned a junked engine block which is to be "cleaned," that is, in which the steel, aluminum and cast iron components of the engine are to be separated. The movement of the splitting blade through the engine block breaks the block longitudinally, separating the pistons, crankshaft and oil pan from the engine.

ENGINE BLOCK BREAKING APPARATUS

BACKGROUND OF THE INVENTION

Separation and salvaging of material in junked internal combustion engine blocks have been, in the past, accomplished by scrap processors through various processes. Primarily, these have involved hand operations, using air hammers, cutting torches, air wrenches and the more elaborate approaches to the problem have envisioned setting up, in effect, disassembly lines. The operation requires a considerable labor expenditure and the danger to workmen, because of relatively uncontrolled breaking or rupturing of the engine blocks, is relatively high. Another prior-art process involves shattering or pulverizing the engine blocks, spreading the fragments on a conveyor and then separating the aluminum, steel and cast iron fragments by hand on the conveyor. The foundry consumers of the end product, however, find the crushed material resulting from this latter process somewhat unsatisfactory from the standpoint of use and handling.

SUMMARY OF THE INVENTION

The apparatus of the present invention utilizes a movable breaking tool which moves between adjustable supports accommodating the engine at its outer, lower margins. The support of the engine block with relation to the moving tool being such that approximately 75 percent of the separation of the steel crankshaft and aluminum pistons from the cast iron block is automatically accomplished by the moving tool or blade and only a minimum of hand separation is required to complete the operation.

BRIEF DESCRIPTION OF THE DRAWING

FIG. 1 is a perspective view of an apparatus embodying the present invention.

FIG. 2 is an enlarged, fragmentary view of the apparatus shown in FIG. 1.

FIG. 3 is a view similar to FIG. 2 but illustrating the apparatus at the different point in its cycle.

FIG. 4 is a view similar to FIG. 3 but illustrating the apparatus in a still further point in its operating cycle.

FIG. 5 is a view similar to FIG. 4 but illustrating the working engaging blade at the extremity of its working stroke.

DESCRIPTION OF THE PREFERRED EMBODIMENT

Referring initially to FIG. 1, the apparatus of the present invention indicated generally at 10 may be serviced by a conveyor 11 having plates 12 thereon accommodating internal combustion engine blocks 13 to be broken up by the apparatus. A conveyor 14 may be utilized to deliver the severed engine block and the parts torn loose from it during the operation of the apparatus. It will be understood that from the conveyor 14 the pieces of the engine block may be deposited upon a plate or further conveyor from which the various loose parts of the block may be segregated either manually or by suitable automatic machinery, not shown.

A fixture 16 mounts the generally rectangular blade 17 which, as may best be seen in FIG. 2, has a tapered lower margin 17a which serves as a block engaging edge. The fixture 16

slides within the uprights 18 and, together with the blade 17 is moved vertically, providing a downward working stroke, by the hydraulic cylinder 19. As may best be seen in FIG. 2, at the base of the conveyor 11, engine block 13, to be processed, is moved by suitable conveying means in a direction parallel to the plane of the blade 17 until positioned directly under it and between the engine block support members 21. Stationary beneath the support member 21 are base elements 22 having flanged margins 22a which overlie inset portions 21a of the support members 21. The support members 21 are slideable horizontally with respect to the stationary members 22, the support members 21 being adjustably moved by any suitable means such as hydraulic cylinders, not shown. As an engine block is moved into the position shown in FIG. 3 directly beneath the blade 17 the support members 21 may be extended toward each other so that the members support or engage the opposite lower side margins 13a of the engine at the oil pan.

In operation, with engine 13 positioned as shown in FIG. 3, the hydraulic cylinder 19 may be actuated to move the blade in its downward, working stroke. With the engine block 13 in position, it will be noted that the blade is generally aligned with the crankshaft 24 extending through the engine block.

As the blade 17 exerts compression on the engine block and moves to an intermediate position in its stroke as shown in FIG. 4, the block will be split longitudinally and further movement of the blade 17 into the extremity of its downward stroke as shown in FIG. 5 serves to break the crankshaft and connected pistons from the cylinder block halves. The blade 17 may then be retracted upwardly and the halves of the engine block and the engine crankshaft, pistons and connecting rods may be deposited upon the conveyor 14 (FIG. 1) for subsequent separation.

It will be noted that the blade 17 moves well through the gap between the support members 21, as shown in FIG. 5, to completely separate the oil pan, crankshaft and pistons from the engine block. The apparatus is sized so that it can be located on the interior of an enclosing structure or building and the engine block processing operation can thus be performed inside under improved working conditions as compared to prior art exterior operations.

I claim:

1. An apparatus for breaking up internal combustion engine blocks comprising a blade having a generally rectangular configuration with a tapered lower margin defining a block engaging edge, the width of said blade being approximately equal to the crankshaft length of the engine block, said blade being supported for vertical movement including a downward working stroke, power means for moving said blade, engine block support members spaced below said blade and on its opposite sides, said blade extending between said support members at the lowermost extremity of its working stroke, said support members being adapted to engage the opposite, lower side margins of the engine block with said blade generally vertically aligned with the engine crankshaft and said support members being movable toward and away from said blade to vary the gap between the support members through which said blade moves, whereby as the working stroke of said blade is completed the crankshaft and connected pistons are broken free of the longitudinally severed engine block.
